CLAIM

The ornamental design for a cutting tool, as shown and described.

DESCRIPTION

FIG. 1 is a front view of a cutting tool of the present design;
FIG. 2 is a rear view thereof;
FIG. 3 is a right side view thereof;
FIG. 4 is a left side view thereof;
FIG. 5 is a top view thereof;
FIG. 6 is a bottom view thereof;
FIG. 7 is a first perspective view thereof;
FIG. 8 is a second perspective view thereof;
FIG. 9 is a cross sectional view taken along line 9-9 of FIG. 1; and,
FIG. 10 is a referential view showing the state in use thereof. The broken lines shown in the drawings represent portions of the cutting tool that form no part of the claimed design.
